UNITED STATES PATENT OFFICE.

GEORGE ALBERT DATSCHEG, OF PHILADELPHIA, PENNSYLVANIA.

SELF-CLOSING HINGE.

No. 868,973.

Specification of Letters Patent.

Patented Oct. 22, 1907.

Application filed December 3, 1906, Serial No. 346,074.

To all whom it may concern:

Be it known that I, GEORGE A. DATSCHEG, a citizen of the United States, residing in the city and county of Philadelphia, State of Pennsylvania, have invented a new and useful Self-Closing Hinge, of which the following is a specification.

My invention relates to a new and useful hinge for gates, doors, etc. and consists in providing means whereby the said gates, doors, etc. are automatically closed and held in the set position, and wherein I provide a small bearing surface and a roller bearing for ease of operation, as will be evident.

It further consists of novel details of construction, all as will be hereinafter fully set forth.

15 Figure 1 represents a perspective view of an upper portion of the hinge. Fig. 2 represents a perspective view of the lower portion of the hinge in separate position. Fig. 3 represents a sectional view of the parts when connected. Fig. 4 represents a sectional view 20 showing the parts in different position from that shown in Fig. 3. Fig. 5 represents a perspective view of the upper portion of the pintle, showing the groove therein. Fig. 6 represents an elevation showing the hinges as applied to a gate.

25 Similar numerals of reference indicate corresponding parts in the figures.

Referring to the drawings: I have found in practice, that in the hinges now in use, it is of advantage to have a self-closing hinge and in addition to provide a bearing 30 surface for the movable parts, which is small in extent and which rests upon roller bearings in order that the hinge may work easily and whereby but little force is required to open the gate.

In the drawing I have shown a construction for carrying out this invention, but it will be evident that other instrumentalities may be employed than those shown, which will accomplish the same results, and I do not, therefore, desire to be limited in every instance, to the exact construction herein shown and described.

40 1 designates a fence having the posts 2, although it will be evident that but a single post may be employed, if desired, where a single gate is used.

In Fig. 6 I have shown two gates, either of which can be opened and will close automatically, and will 45 scribe but one of these, as any number may be employed.

3 designates a bracket which is secured in any desired manner, in the present instance, by means of bolts passing through the openings 4, to the post 2, or other 50 suitable support. In connection with and forming part of said bracket, is a pintle 5, having a groove 6 in its upper portion, and the upper face of which is beveled or inclined at 7. Adapted to be situated in said groove

and projecting slightly above the plane of the beveled surface 7 are the two roller bearings 8 and 9. It will be 55 noticed that the face opening of the groove is smaller than the diameter of the roller bearings and that therefore these bearings while permitted to rotate are prevented from moving from their position, the advantages of which are evident.

60 10 designates a socket which is adapted to fit said pintle 5 and rotate around the same, as will be herein-after described, said socket having secured thereto a pin 11 which, in the present instance, is secured by the screw 12, although any desired means for securing 65 the same may be employed. The lower face of said pin is provided with the inclined faces or tracks 13 which are formed by having a recessed portion 14 therebetween, it being noted that said tracks are adapted to rest upon the roller bearings 8 and 9 when the parts are 70 in position, as understood from the Figs. 3 and 4.

15 15 designates a standard suitably connected to the pin and around which is situated a sleeve 16 which is provided with a socket 17 adapted to receive a rail 18 of the gate, a lug 19 being connected with said socket 75 and sleeve and is adapted to have connected therewith, a portion 20 forming a part of the gate. The upper portion of the standard 15, when the parts are in position, moves in a suitable bracket 21 connected with the post or support 2.

80 The operation of the parts will be readily understood. When the sleeve 10 is rotated upon the pintle 5, depending upon which direction the sleeve is rotated, one or other of the tracks 13 will move on the roller bearings 8 or 9 so that the sleeve 10 and its connected 85 parts will be elevated, this being easily accomplished by reason of the narrow extent of the bearing surface 13 and by reason of the roller bearings 8 and 9, the advantages of which are evident. By this means it will be seen that when the gate 22, which is carried by the 90 hinge, is moved in either direction, it will be slightly elevated and when released, the same will be immediately closed and remain in this position until again moved.

Having thus described my invention, what I claim as 95 new and desire to secure by Letters Patent, is:—

1. In a device of the character described, a pintle rigidly supported, an inclined face on said pintle having a groove extending across the same, roller bearings in said groove, said groove being smaller than the diameter of said roller 100 bearings, a socket encircling said pintle, an inclined track carried by said socket bearing on said rollers, whereby when the parts are turned the socket will be elevated on said pintle.

2. In a device of the character described, a pintle rigidly supported, an inclined face on said pintle having a groove extending across its surface, roller bearings rotatably mounted in said groove projecting slightly be-

yond the inclined face and prevented from lateral displacement, a socket encircling said pintle, an inclined track carried by said socket bearing on said rollers whereby when the parts are turned, the socket will be elevated on said 5 pintle.

3. In a device of the character described, a pintle having an inclined upper face, a groove extending across said face, a roller bearing rotatably mounted in said groove and prevented from lateral displacement thereby, a socket

movable on said pintle, inclined tracks carried by said 10 socket bearing on said roller, and a socket connected with said first mentioned socket and adapted to receive a suitable portion of a gate.

GEORGE ALBERT DATSCHEG.
